UNITED STATES PATENT OFFICE

106,445

DESIGN FOR AN AUTOMOTIVE VEHICLE RADIO ANTENNA

Andrew B. Lail, Washington, D. C.

Application May 24, 1937, Serial No. 69,533

Term of patent 14 years

To all whom it may concern:

Be it known that I, Andrew B. Lail, a citizen of the United States, residing at 3900 14th St., N. W., in the city of Washington, District of Columbia, have invented a new, original, and ornamental Design for an Automotive Vehicle Radio Antenna, of which the following is a specification, reference being had to the accompanying drawing, forming part thereof, in which:

Figure 1 is a side view of an automotive vehicle radio antenna showing my new design; and

Figure 2 is a plan view thereof.

The device of applicant's design is adapted to be used on an automotive vehicle body.

The antenna is characterized by having two spaced fixed bowed members which are joined at one end by inwardly turned reverse curved portions, said members being also gradually curved laterally from end to end.

I claim:

The ornamental design for an automotive vehicle radio antenna, substantially as shown and described.

ANDREW B. LAIL.
